UNITED STATES PATENT OFFICE.

EDWARD J. GULICK, OF MISHAWAKA, INDIANA.

EXHAUST-MUFFLER.

No. 874,676.

Specification of Letters Patent.

Patented Dec. 24, 1907.

Application filed February 13, 1907. Serial No. 357,153.

To all whom it may concern:

Be it known that I, EDWARD J. GULICK, a citizen of the United States, residing at Mishawaka, in the county of St. Joseph and State of Indiana, have invented certain new and useful Improvements in Exhaust-Mufflers, of which the following is a specification.

The invention is primarily adapted for use in connection with gasoline engines where the exhaust from the cylinder is expelled at a pressure between two and three times an atmosphere, and which would result in considerable noise if it were not for the use of a muffler in connection therewith.

Although there are many mufflers of different forms, their object is all the same, and that is to "break-up" the exhaust gases by expelling them through perforations in an exhaust tube, and permitting them to expand to nearly atmospheric pressure before leaving the muffler or the exhaust tube. As the perforations prevent the free expansion of the exhaust gases, there is consequently a back pressure upon the engine as well as a detonation which is due to the gases, after each explosion, leaving the muffler together although in a reduced form.

My invention has for its objects to provide a muffler wherein the exhaust gases are broken up and expanded to nearly atmospheric pressure and are then expelled from the muffler in a progressive form, making a continuous stream therefrom.

The invention consists in general of a main chamber in which the exhaust gases are discharged from the cylinder and a series of auxiliary chambers communicating with the main chamber by perforations that differ in number or size, and the auxiliary chambers communicating with each other whereby the exhaust gases pass from the main chamber into the auxiliary chambers and progressively from one auxiliary chamber to the next until the discharge port is reached in one of the auxiliary chambers whereupon it passes into the outside atmosphere.

In the accompanying drawing Figure 1 is a side elevation of my device; Fig. 2 is a longitudinal section of Fig. 1; Fig. 3 is an end elevation of Fig. 1 with parts in section; and Fig. 4 is a cross-section on line 4—4 of Fig. 1.

Referring now more particularly to the

drawing, and to the construction in general, 5 represents an inner casing, cylindrical in form, and 6 represents an outer casing inclosing the inner casing and being properly held apart by the heads 7 and 8, which are provided with the inwardly extending circumferential flanges 9 and 10, the inner casing surrounding the flange 10 while the outer 60 casing fits within the flange 9, the ends of the cylinders or casings being closed by the heads which are held together by the stay rods 11 and the bolts 12 at each end thereof. The head 7 is provided with an annular intake 65 port 13 opening directly into the inner casing and screw threaded at 14 to form a suitable connection to the discharge pipe from the cylinder, while the head 8 is provided with an annular exhaust opening 15, for a purpose 70 hereinafter described. Interposed between the outer and inner cylinders or casings are a series of partitions 16, 17, 18, 19, 20, 21, 22, 23, 24, 25, 26 and 27 that run longitudinally of the casings and form the auxiliary chambers or compartments 16^a, 17^a, 18^a, 19^a, 20^a, 21^a, 22^a, 23^a, 24^a, 25^a, 26^a, and 27^a. The partition 16 extends the full length of the inner casing abutting against the heads thereof; the next partition 17 to the right 80 (Fig. 4) terminates slightly short of the head 7, as seen in Fig. 2. The next partition 18 terminates short of the head 8 although abutting against the head 7, and so the partitions alternate in abutting and terminating 85 short of the different heads entirely around the inner casing so as to form a continuous zig-zag passage from the partition 16 through the different auxiliary chambers 16^a, 17^a etc., until the chamber 27^a is reached which is 90 provided with an exhaust port 28. The partitions in the form herein shown have their edges bent inwardly, as shown at 29, and riveted to the outer and inner casings. The inner casing is provided with a series of perforations 30 that open into the auxiliary chambers, the greatest number of perforations opening into the auxiliary chamber 16^a and the number thereof gradually diminishing in each successive auxiliary chamber, until the 95 auxiliary chamber having the least number of perforations is chamber 27^a, which is provided with the exit port 28. It is not necessary that there be a definite number of perforations.

rations, nor is it necessary that they be of any specific size as they might vary according to the type of engine that the muffler was used in connection with, but in the ordinary 5 form the area of the perforations would be sufficient to admit all the exhaust gases from one discharge of the engine directly into the auxiliary chambers.

Referring now to what is termed the cut-10 out on a muffler, 31 represents a valve adapted to close the exhaust port 15, which is provided with a valve stem 32 slidably mounted through the plate 33 that is secured to the lugs 34, that are formed integral with the 15 head 8 and are so spaced as to form the passages 34^a through which the exhaust gases are discharged. A spring 35, the tension of which is normally outward to seat the valve, is mounted on the outer end of the valve 20 stem and is held against the plate 33 by the block 36 that is preferably formed integral with the lever arm 37 and with which the valve stem has a threaded connection. The lever arm is pivoted at 38 to a lug 39 formed 25 integral with the head 8. The lever arm is provided with an eye 40 for connecting it with the operating means, and the action is to press the valve inward whereby the exhaust gases in the inner chamber may be in-30 stantly released without passing through the perforations, it being understood, however, that the cut-out as herein shown is not part of my invention and is such as is commonly employed upon mufflers.

Referring now more especially to the movement of the discharged gases, we will assume that an explosion has occurred in the cylinder and the gases are forced through a discharge pipe connected thereto and pass 35 into the inner chamber, the valve of the cut-out being closed, the gases being in a heated stage immediately expand and pass through the perforations 30 in the inner cylinder to the auxiliary chambers. The pressure being 40 equal throughout the whole inner chamber the gases will not pass into the auxiliary chambers in equal amounts due to each auxiliary chamber having a different number of perforations that communicate with the 45 main chamber. The chamber therefore having the greatest number of perforations will receive the largest volume of gas first, that chamber being 16^a. The gases will pass through the auxiliary chamber 16^a down to 50 the end of the partition 17, circulating around the end thereof back the full length of the auxiliary chamber 17^a, around the end of the partition 18, then through the next auxiliary chamber 18^a and so on around 55 the various auxiliary chambers, so referring to Fig. 4 the exhaust gases would pass from chamber 16^a to 17^a etc., until chamber 27^a was reached, where they would be

expelled through the discharge port 28. The exhaust gases that pass into the auxiliary 65 chamber 22^a would pass into the auxiliary chamber 23^a and so on around to the chamber 27^a, while the exhaust gases discharged into the chamber 27^a would immediately 70 pass out. It can be thus readily seen that 75 there is a progressive movement of the exhaust gases from one auxiliary chamber to another and so on through all the auxiliary chambers. On account of the numerous partitions used to construct the auxiliary 80 chambers, the cooling of the gases is accomplished because the partitions are directly connected to the outer casing which is surrounded by the free air, so that the gases will be practically at the same atmospheric 85 pressure as the free air when discharged through the port 28. It will be readily seen that the discharged gases do not leave the muffler at one time, but are broken up and expelled into the numerous auxiliary chambers which in turn distribute the discharge in such a manner that the discharge from one chamber is not expelled through the port 28 until the discharge from the chamber next nearest the port 28 is first expelled, thereby 90 causing gases to be expelled from the muffler in a continuous stream rather than in a body, which causes the heavy detonations.

I claim:

1. An exhaust muffler comprising a main 95 chamber into which exhaust gases are expelled, a series of auxiliary chambers surrounding said main chamber and communicating therewith by perforations formed in said main chamber, the total area of the perforations communicating with each auxiliary chamber varying, said auxiliary chambers being in communication with each other at their ends, a discharge port in one of said auxiliary chambers whereby exhaust gases 100 discharged into said main chamber pass into said auxiliary chambers and are expelled through said discharge port, substantially as described.

2. In an exhaust muffler an outer and an 110 inner casing, a series of auxiliary chambers formed between said casings and communicating with each other at their ends to form a continuous zig-zag passage through all of said auxiliary chambers, each of said auxiliary chambers communicating with said inner casing, a port in said inner casing for admitting exhaust gases therein and a port in one of said auxiliary chambers through 115 which the exhaust gases are expelled, substantially as described.

3. In an exhaust muffler, the combination of an outer casing and an inner casing, a series of partitions radially interposed between said casings and secured thereto, to form auxiliary chambers, each of said auxiliary cham- 125

bers communicating with said inner casing by communications of unequal area, said auxiliary chambers being in communication at their ends with each other, and a discharge port in one of said auxiliary chambers whereby exhaust gases discharged into said main chamber pass into said auxiliary chambers

and are expelled through said discharge port, substantially as described.

EDWARD J. GULICK.
